UNITED STATES PATENT OFFICE.

JOHN STEVENS, OF PORT BYRON, ASSIGNOR TO THE SYRACUSE FIBRE
WARE COMPANY, OF SYRACUSE, NEW YORK.

MACHINE FOR FORMING VESSELS FROM PAPER-PULP.

SPECIFICATION forming part of Letters Patent No. 355,625, dated January 4, 1887.

Application filed July 21, 1884. Serial No. 132,378. (No model.)

To all whom it may concern:

Be it known that I, JOHN STEVENS, of Port Byron, in the county of Cayuga, in the State of New York, have invented new and useful 5 Improvements in Machines for Forming Vessels from Paper-Pulp, of which the following is a specification.

This invention relates to an improvement in that class of machines which are employed for 10 forming the hollow bodies of paper vessels—such as pails, barrels, &c.—by winding a web of soft paper stuff upon a suitable mandrel until a body having the desired thickness has been deposited thereon.

15 The object of this invention is to improve the operation of this class of machines; and it consists in the improvements which will be hereinafter fully set forth, and pointed out in the claims.

20 In the accompanying drawings, Figure 1 is a sectional front elevation of my improved machine. Fig. 2 is a sectional side elevation thereof. Fig. 3 is a detached front view of the pivoted support to which the forming-mandrels are attached. Fig. 4 is a perspective view of the removable metallic jacket.

Like letters of reference refer to like parts in the several figures.

A represents the tank which receives the 30 pulp.

B represents the drum arranged in the tank A, and provided with a perforated or reticulated peripheral wall in the usual manner.

C represents a pump of any suitable construction, whereby the water is drawn from the 35 interior of the depositing-drum B, thereby causing the paper-pulp to be deposited against the outer side of the drum.

D represents the coucher-roller covered with 40 felt and arranged above the depositing-drum B, so as to run in contact with the upper side thereof, and receiving the web of soft paper stuff therefrom.

E represents a pressure-roller bearing 45 against the web of soft paper stuff on the ascending side of the coucher D, for the purpose of pressing any excess of moisture from the web.

F represents a clearing-roller bearing 50 against the descending side of the coucher, and removing any portions of paper stuff

which may adhere to the felt with which the coucher is covered.

f represents a scraper attached to a support, f', and bearing against the clearing-roller F, 55 for the purpose of removing the paper stuff from the roller F, which the latter has taken from the coucher.

g represents a perforated pipe arranged above the contiguous portions of the rollers D 60 and F and delivering a spray of water upon the same, for the purpose of facilitating the removal of the shreds of paper stuff from the coucher D.

H, H' represent two forming-mandrels 65 mounted upon arbors h, which are secured with their rear ends to a two-armed support, I. The latter is secured to a shaft, i, which is supported in bearings j.

JJ are supports secured at their lower ends to the tank A, and provided at their upper ends with bifurcated portions or parallel bars j', between which are arranged the bearings j, in which the shaft i is journaled. The upper ends of the bifurcated portions j' are connected 70 by cap-pieces j'', through which pass adjusting-screws j', whereby the bearings can be raised and lowered between the bars j', in order to adjust the forming-mandrels toward or from the coucher. The arbors h are rigidly secured 75 to the arms of the support I, and the mandrels H turn on said arbors. By turning the support I either of the mandrels H can be brought in contact with the coucher, so that one of the mandrels can receive the soft paper stuff from 80 the coucher, while the complete body of paper-pulp is removed from the other mandrel and the latter again prepared for receiving another deposit of paper-pulp.

K represents jackets, constructed of zinc or 85 other suitable metal, and adapted to be removably applied to the mandrels H. The jackets K are divided lengthwise, and the contiguous longitudinal edges of each jacket are bent inwardly, forming ribs k, which engage in a longitudinal groove in the mandrel and hold the jacket against turning on the same.

L represents an elbow-lever, pivoted to the front side of the support J, below the pivoted 90 support I, and bearing with its short arm l against a nose or projection, m, formed at each

end of the pivoted support, as represented in Fig. 3. The weight at the end of the long arm of the lever L tends to hold the lever in the position in which it is represented in the drawings.

As the thickness of the layer of pulp on the lower mandrel H increases it causes the support I to turn on the shaft i in the direction of the arrow in Fig. 3, thereby raising the weighted arm of the lever L. The overlapping surfaces of the short arm l and nose m are made so long that the nose will disengage itself automatically from the short arm l when a layer of pulp of the required thickness has been deposited upon the lower mandrel H. The weight causes the lever L to return to its former position as soon as the mandrel has released itself from the lever, and the long arm of the lever L is retained in its normal position against further downward movement by a stop, n. The layer of pulp which is deposited upon the drum B passes from the drum to the coucher D, and thence upon the lower forming-mandrel H, as indicated in Fig. 1. The successive convolutions of pulp are deposited upon the mandrel H until a body of the required thickness has been formed, when the lower mandrel disengages itself automatically and severs the soft web of paper stuff. The upper mandrel, being previously provided with a metal jacket, K, is now swung down in contact with the coucher D, and the web of paper stuff now passes around the last-mentioned mandrel, while the deposited body of paper stuff is removed from the first-named mandrel, together with the metal jacket upon which it was deposited. The jacket is removed from the interior of the deposited body of paper-pulp by collapsing the jacket. In this manner the web of paper stuff is alternately wound upon the two mandrels, whereby hollow bodies of paper-pulp of uniform size and thickness are rapidly produced.

When the machine is used for forming the

bodies of paper pails, the depositing-drum B, 45 coucher D, and forming-mandrels H are all tapered, as represented in the drawings, corresponding with the taper of the pail to be produced; but if a vessel of cylindrical form is desired, all of these parts are made cylindrical. 50

I claim as my invention—

1. The combination, with the pulp-depositing drum and coucher, of interchangeable forming-mandrels mounted upon a pivoted support and a locking device, whereby the pivoted support is held in position until the desired thickness of pulp has been wound upon the mandrel, substantially as set forth. 55

2. The combination, with a pulp-depositing drum and coucher, of interchangeable forming-mandrels mounted upon a pivoted support and an automatic locking device which holds the pivoted support in position and releases the same automatically when the desired thickness of pulp has been deposited 65 upon the mandrel, substantially as set forth.

3. The combination, with the pulp-depositing-drum B, coucher-roller D, forming-mandrels H, and pivoted support I, of the weighted lever L, substantially as set forth. 70

4. The combination, with the depositing-drum B, coucher-roller D, and forming-mandrels H, of the pressure-roller E, bearing against the coucher-roller on its ascending side, on which the paper is carried to the mandrel, substantially as set forth. 75

5. The combination, with the depositing-drum B, coucher D, and forming-mandrels H, of the clearing-roller F, bearing against the coucher-roller on the descending side thereof, 80 spray device g, and scraper f, substantially as set forth.

Witness my hand this 7th day of May, 1884.

JOHN STEVENS.
